UNITED STATES PATENT OFFICE.

WILLIAM RYDER AND EDWARD RYDER, OF NEW BRUNSWICK, NEW JERSEY, AS
SIGNORS TO RECKITTS (U. S. A.) LTD., OF NEW YORK, N. Y., A CORPORATION OF
GREAT BRITAIN,

PACKAGE-TYING DEVICE.

Original application filed February 3, 1922, Serial No. 533,884. Divided and this application filed October 30, 1923. Serial No. 671,698.

To all whom it may concern:

Be it known that we, WILLIAM RYDER and EDWARD RYDER, citizens of the United States, residing at New Brunswick, in the county of Middlesex, State of New Jersey, have jointly invented new and useful Improvements in Package-Tying Devices, of which the following is a specification.

The invention relates to a machine for tying a package and in its present embodiment is particularly designed to tie a piece of string around the open end of a wrapper partially enclosing a cylindrical shaped piece of laundry blue. However the knotting mechanism could readily be adopted to tie and knot a string around a package of any desired shape.

In the tying mechanism as disclosed, means are provided for carrying the string around the open end of the package, the string gathering the wrapper together, and other means are provided for looping the string. The free end of the string is carried through the looped portion and while the string is being held, the looped portion is tightened and the knot is formed.

The knot tied by this machine and which it is preferable to use is a square, or reef knot. After the knot has been tied, suitable cutting mechanism cuts the string and holds the end coming from the supply, so as to be in readiness for the next cycle.

Novel safety devices are provided to stop the machine in case the string should break or become tangled or knotted, prior to entering the machine.

The parts of the mechanism are so designed and constructed that, despite the intricate work that is accomplished, they are positive and accurate in their action and will not readily get out of order, and if it should happen that the parts do get out of order, or need adjusting, the operator can take care of them. The parts and movements on the mechanism are all accessible for adjustment, or other purposes.

The invention comprises improvements in tying devices, the claimed subject matter constituting a division of our application Serial No. 533,884, filed Feb. 3, 1922.

Numerous other, novel features and advantages will be brought out in the following specification and illustrated in the accompanying drawings forming a part thereof. Referring to said drawings:

Fig. 1 is a top plan view of the entire machine, with the parts in the position they would assume while the machine is not in operation.

Fig. 2 is an end elevation looking from the right of Fig. 1, showing the parts in the same position as they are shown in Fig. 1.

Fig. 3 is a sectional bottom plan view taken on the line 3—3 of Fig. 2, on a somewhat larger scale.

Fig. 4 is an enlarged, fragmentary, detail view of the mechanism for stopping the machine, when the string breaks or becomes knotted.

Fig. 5 is a front view of the mechanism shown in Fig. 4.

Fig. 6 is a sectional view taken on the line 6—6 of Fig. 5.

Fig. 7 is a detail sectional view taken on the line 7—7 of Fig. 1. This view shows particularly the slide which carries the looping mechanism and the cam operating said mechanism.

Fig. 8 is a detail sectional view taken on the line line 8—8 of Fig. 1. This view shows particularly the slides which carry the looping mechanism and the tensioning mechanism, respectively.

Fig. 9 is a detail cross sectional view taken on the line 9—9 of Fig. 10. This view shows particularly the slide which carries the knot tightening mechanism.

Fig. 10 is an enlarged top plan view showing the slides which operate the knot tightening mechanism and the end of the slide carrying the looping mechanism and also parts of the knot tensioning mechanism.

Fig. 11 is a view similar to Fig. 10 with a number of the parts left off for simplifying the illustration and showing the parts in another position.

Fig. 12 is a detail sectional view showing the string cutting mechanism, the view being taken on the line 12—12 of Fig. 11.

Fig. 13 is a view similar to Fig. 12 show-

55

ing the cutting mechanism in another position. In this view the parts of the mechanism are in the same position as in Fig. 11.

Fig. 14 is a sectional view taken on the line 14—14 of Fig. 12.

Fig. 15 is a detail sectional view showing the operating means for the device that holds the end of the string while the knot is being tied, and the stop which controls the 10 rotation of the looping members. This view is taken on the line 15—15 of Fig. 3.

Fig. 16 is an enlarged plan view showing the slide which carries the tensioning mechanism and other adjacent parts of the 15 machine.

Fig. 17 is a sectional view taken on the line 17—17 of Fig. 16.

Fig. 18 is an enlarged sectional view taken on the line 18—18 of Fig. 1. This view 20 shows particularly the slides which control the knot tightening mechanism.

Fig. 19 is a front view of the parts shown in Fig. 18.

Fig. 20 is an end elevation of the stationary cam, operating part of the knot tightening mechanism. This view also shows the pawl and toothed wheel which takes care of the back lash in the machine.

Fig. 21 is a cross sectional view of the cam shown in Fig. 20, the view being taken on the line 21—21 of Fig. 1.

Figs. 22 and 23 are sectional views, showing the needle and its operating mechanism in two different positions.

Fig. 24 is an elevation of a set of driving gears and pinions, showing position of same when machine is momentarily stopped during the tightening of the first loop of the knot.

Fig. 25 is a similar view taken on the line 25—25 of Fig. 1.

Figs. 26 and 27 are views similar to Figs. 24 and 25 showing the parts in another position.

Fig. 28 is a detail sectional view taken on the line 28—28 of Fig. 16, showing the method of holding the string on the end of the tensioning device slide.

Figs. 29 to 36 are schematic plan views 50 showing the different positions the parts assume while the string is being looped and the wrapper for the article to be wrapped is being gathered together preparatory to the final tying of the knot.

Figs. 37 and 38 are schematic views, showing further steps in the tightening of the knot.

Figs. 39 to 43 are enlarged schematic views showing different positions the string 60 assumes while the knot is being tied.

Fig. 44 is an elevation, showing the final result after the machine has wrapped and tied the article, cut the string and ejected it from the machine.

Fig. 45 is a partial front elevation, show-

ing the position the parts would occupy while the machine is in operation.

Fig. 46 is a fragmentary detail cross sectional view on a large scale, taken on the line 46—46 of Fig. 3.

The wrapping of the article and conveying it in a partially enveloped condition to the tying mechanism is fully described and claimed in the application, Serial No. 533,884, of which this case is a division. Therefore the mechanism doing this will not be described to any great extent in this specification.

The machine has a bed plate, 1, supported upon legs 2 and 3. Mounted in bearings 4, secured to the leg 3, is a vertical shaft 5. Fixed to the upper end of the shaft 5 is a hub 6, provided with spokes 7, which are connected to the large ring or carrier 8, thus providing the driving connection for the 85 ring or carrier.

The carrier is supported on small rollers 9^a, mounted on the ring 9, which has a segment thereof omitted for reasons hereafter explained.

The carrier 8 has secured to it a plurality of holders 13. Each holder 13 is located over the supporting ring 9 and holes are provided in the carrier the same diameter as the inside of the holders and located directly under each holder.

At the front of the machine supported on a plate 10 is a bracket 14 which carries a shallow pan or plate 15, preferably of the shape of the covering to be used for wrapping the article. In this instance since a square wrapper is being used, the pan is made square. The pan has an arcuate slot 16 extending from its right hand end and approximately to the central portion thereof. The movement of the carrier is so arranged that a holder always stops directly under the closed end of the slot as seen in Fig. 1.

While held in this position by suitable mechanism, the operator lays in the pan a square piece of cloth, which being approximately the same size as the pan, covers it. A piece of blue or the article to be wrapped is then forced down by the operator, until it touches the supporting ring 9. The carrier is then rotated, the free ends of the covering passing through the slot 16, and the operator fills the next holder as it is brought under the pan.

Suitable means are provided to rotate the 120 carrier intermittently and consist of a ratchet wheel and pawl 17 and 18 (Fig. 2) which are operated through suitable linkage from the shaft 29 carried in bearings 30, secured to the frame or legs 2 and 3.

Attention is called at this time to the fact that while the operator is feeding into one of the holders an article to be wrapped and its covering, the carrier is held stationary and tying mechanism designated generally "A" 130

(Fig. 1) is operating to wrap and tie the article. An ejector, afterwards described, is also at this time forcing from its respective holder one of the articles that has been completely wrapped and tied. The elements of the machine are so timed that this takes place while the carrier is stationary. While the carrier is being advanced one step, the tying mechanism designated "A" is held out of operation and suitable means are provided for doing this.

A shaft 40, parallel to the shaft 29 is supported in bearings 41 and carries a sprocket wheel 42 which is loosely mounted on the shaft 40. Through the medium of a sprocket chain 43 and sprocket wheel 44 mounted on the shaft 29, the sprocket 42 is driven. The shaft 40 carries all the cams which operate the tying mechanism. By means of a suitable clutch, indicated at 48, and operated by the levers shown in Fig. 2 the sprocket wheel 42 revolves the shaft 40 only at such times as it is desired to operate the tying mechanism.

Notches 74 in the carrier are engaged by a pin 73 mounted on the lever 71. This pin is caused to engage with the notches 74 when the carrier is held stationary.

The string α is supplied from a bobbin, spool, ball or any other suitable source, not necessary to illustrate, and is led through a hole 84 in a pivoted member 85. (See Figs. 1 and 16.) This member guides the string, but primarily it operates a mechanism which stops the machine in case the string is tangled or knotted prior to entering the machine and passing through the hole 84 in said member 85. This pivoted member 85 is also part of the mechanism which stops the machine, if the string breaks while in the machine. The operation of this mechanism will be explained later.

From the hole 84 in the member 85 the string is led through a fixed eye 86 on the end of a reciprocating slide 87, Figs. 16 and 17. This slide is dovetailed and mounted in a bracket 88 secured to the bed plate, the slide being held in place by retaining strips 89. (See Fig. 17.)

The string then passes through a gripping device 90 for holding it firmly while the knot is being tied. Fig. 28 shows the gripping device and its actuating mechanism holding the string. The gripping device consists of a hollow post 91 riveted or otherwise secured near the outer end of the slide 87. The upper part of the post is counterbored and provided with two slots or openings 92 diametrically opposite each other, through which the string passes. Two keyways 93 are also provided to accommodate a pair of ears 94 on the head 95 of a rod 96 which fits in the bore of the post 91. The rod 96 has a passage 97 through it, in line with the slots 92 so that when the pin is raised as is shown

in Fig. 25, the string is free to pass through, but when the pin is lowered as in Fig. 28, the string is firmly gripped and held against movement in either direction. The lower end of the rod 96 has a pin 98 passing through it, which confines a spring 99 between said pin and the bottom of the slide and tends to pull the head 95 of the rod 96 down to grip the string.

A bracket 100 secured to the underneath part of the slide 87 has pivoted therein at 101 a detent 102. This detent 102 is engaged by an extension 103 held to the bed plate. When the slide is in its outward position, as in Fig. 28, the detent 102, being loosely mounted, allows the spring 99 to function, thus pulling the rod down and gripping the string. When the slide is pulled inward by suitable mechanism, afterward described, the detent comes in contact with the member 103, and the rod 96, is forced upward, thus allowing the string to be freely drawn through the gripping device 90.

The string next passes through the eye of a stud 104 forming part of a tensioning device, the operation of which will hereafter be described and thence the string passes over a spool 105 rotatably mounted on a stud 106 secured to the slide 87. From the spool 105 the string passes through the eye of another stud 107 similar to 104 and forming part of the aforesaid tensioning mechanism. The string then passes over another spool 108, mounted on a stud 109 secured to said slide 87.

Pivoted on the stud 109 which carries the spool 108 is a lever 110 which carries an upright pin 111 around which the string is passed. This lever has one end of a spring 112, attached to it, the other end of said spring 112 being attached at any convenient place to the slide 87. As shown in Fig. 16, the slide is in its inward position and the gripping device 90 is released, and in this position as there is no tension on the string, the spring 112 will hold the lever 110 in the position shown in said Fig. 16, as the lever has a downward extension 113 (Fig. 17) which bears up against the bracket 88 and will not permit it to move.

The tensioning device previously mentioned of which the two studs 104 and 107 form a part, consists of a long curved arm 114 loosely pivoted on the stud 115. Fixed by a set screw 116 to the stud 115, is a three armed member 117. The arm 118, of this member 117, bears an upstanding flange 119 to which is secured at its outer end, by means of an adjustable screw connection 120, a spring 121. The opposite end of the spring 121 is secured by another adjustable screw connection 122, to the outer end of the free arm 114. Near the pivot 115 of the arm 114 is a toe 123 integral with said

arm. An adjustable screw connection 124 bears against, and positions the arm 114, shown in Fig. 16.

Another arm 125 of the member 117 has 5 pivoted at its outer end 126 a link 127 which in turn is pivoted at 128 to a member 129 which is riveted, or otherwise secured, to the slide 87.

When the member 117 is moved in the direction of the arrow 130 in Fig. 16, the slide 10 87 is moved outward through the medium of the arm 125, the link 127, the part 129, while the gripping device 90, is holding the string. At the same time it will be clear 15 from an inspection of the drawings that the arm 118 through the spring 121, is pulling the arm 114 which carries the studs 104 and 107, through the eyes in the heads of which the string passes, away from the slide or 20 position shown in Fig. 16. The free end of the string is held in another gripping device, hereinafterwards described. The device just described is for the purpose of tensioning or tightening the string, while the 25 knot is being tied.

Referring again to the lever 110, it is clear from the foregoing description that, when the string is being tensioned, said string will tend to form a straight line between the roller 108 and the fixed eye 131, attached to the slide 87. Thus, when the slide 87 is moved outward, the downward extension 113, being moved in the direction of the arrow 132, will avoid the lug or projection 133, on a slide 134. If the string should break, the lever 110 would not be moved from the position shown in Fig. 16, when the slide 87 is moved outward, and said downward extension 113 would come 30 in contact with the projection 133, and would move the slide 134 outward, where it would come in contact with the vertical slide 135, and would operate suitable mechanism, to be described hereafter, to stop the machine. 45

The bracket 136 guides the lever 110 and prevents any up and down movement of the lever. Thus it is clear that the purpose of the lever 110 and the slide 134 is to form 50 part of a device for stopping the machine, in case the string breaks. The slide 134 is slotted, and studs 137 passing through the slots, are secured to the bed plate. A spring 138, one end of which is fastened to the slide 134 and the other end to one of the studs 137, keeps the slide withdrawn, except at such times as it is forced outward by the downward extension 113, of the lever 110.

From the fixed eye 131, the string passes 60 through another tensioning device 140. The purpose of this tensioning device is to remove slack, and particularly to keep taut that part of the string between a fixed eye 141, secured to the slide 87, and the string holding and cutting mechanism 142, also

mounted on the slide 87. This part of the string designated α^1 in the drawings is grasped by the needle when it begins to draw through the devices attached to the slide 87, the amount of string required for 70 tying one article. The needle and its operating mechanism will be described herein-after.

The tensioning device comprises a standard 143, secured to the slide 87, and having 75 a pivot pin 144 in its upper part, on which is pivoted a tensioning member 145. The lower part of this member is bifurcated and each arm has a hole 146 therein, to allow the string to pass through. 80

Mounted at the lower part of the standard 143 (see Fig. 8), is a clamp or friction mechanism 147, which holds the string, but holds it only tightly enough so that when the needle grasps said string, it will pull it 85 through said mechanism 147. The mechanism 147 consists of fixed jaw 148, in which is pivoted at 149 a movable jaw 150. These two jaws provide a restricted V shaped opening 151, for the string. A spring 152, 90 between the jaws 148 and 150, normally tends to restrict the opening 151 and to hold the string until the pull of the needle is sufficient to move it. This mechanism is shown particularly in Figures 8, 16, and 17. 95 As shown in Fig. 16, the string passes from the fixed eye 131, through the hole 146 in one arm of the bifurcated member 145, thence through the opening 151 and through the hole 146, in the other arm of the bifurcated member. The string then passes through another fixed eye 141, and thence to the cutting mechanism 142. 100

A light spring 153, one end of which is secured to the pivot pin 144 and the other end to the standard 143, forces the member 145 downward, or in the direction of the arrow 154. Secured to the tail 155 of the member 145, is a stronger spring 156, the other end of which is secured to one arm 157 of a bell crank lever, pivoted on the stud 109. The other arm 158 of the bell crank lever comes in contact at the proper time with a pin 159, secured to another slide 160. Thus the member 145 will be forced in the 110 direction opposite to the arrow 154 and working in conjunction with the mechanism 147, will take the slack out of the string, particularly that part, as explained before, of the string between the mechanism 147, 115 and the cutting and holding mechanism 142. The mechanism 142 will be described hereinafter.

As explained before, the slide 87 is operated from the stud 115, which passes 120 downward through the bed plate and has attached to its lower end a short lever 161 (Fig. 3), which has a slot 162, in which is pivoted at 163 the end of a rod 164. The rod has attached to its opposite end a 125

slotted member 165, which embraces the shaft 40 and carries a cam roller 166, which in turn engages the cam groove in the face cam 167, secured to the shaft 40. The disc 5 168, secured to the shaft 40, keeps the member 165 in position.

Attention is now directed to the slide 160-170, which carries the looping and mechanism and part of the knot tightening 10 mechanism. This slide is reciprocated by suitable mechanism in a slot 169 in the bed plate (Fig. 8). The slide has a top plate 160 and bottom plate 170, both secured to the block 171. The lower plate is held in 15 guides 172 (Figs. 3 and 8), which are screwed or otherwise secured to the bed plate. This lower slide or plate 170 carries the operating mechanism for some of the parts carried on the upper slide or 20 plate 160.

The upper plate 160, as previously mentioned, carries the pin 159, which at the proper time operates the tension device 140. Adjacent the pin 159, and secured to the 25 plate 160, is a lug or projection 173, which engages at the proper time with an adjustable screw 174 on the tail 175 of a string depressing lever 176 (Fig. 17). The string is caught under the shoulder 177 on the 30 inner or free end of the lever 176. As the slide is moved inward the stop 173 leaves the screw 174, and the lever will be pulled down by the spring 178. The lever is pivoted at 179 to the bracket 88.

35 Before the slide 160 commences to move, the needle 180 is brought over and takes hold as previously mentioned of that part of the string designated α^1 . The needle and its operating mechanism will now be described.

The part designated as the needle is made of two pieces, the outer piece 181, being substantially U shaped and embracing the inner or slidable piece 182 (Fig. 23). The 40 front part of the needle, as shown in Figs. 30 and 31, is cut down to enable it to pass under the spokes 7 of the carrier 8, and the string depressing lever 176 (see Fig. 29). The inner slidable piece 182 is provided at 45 its forward or gripping end with a head 183, which has a curved contour, to allow it to slip under the string easily. As it is brought up to the string, suitable mechanism projects said head 183, on the inner 50 piece forward, and the string slides into the gap between the end of the outer piece 181 and the head 183 of the inner piece, as seen in Fig. 31. This gap is then closed and the string is thus firmly grasped by the end of 55 the needle. After the string has been looped, and prior to tightening the knot, the string is released from the needle.

The end of the needle opposite the gripping end is carried on a stud 184 (see Figs. 60 3-22 and 23), which is swiveled on a le-

ver 185, which in turn is pivoted at 186 to a bracket, secured to the bed plate. This lever 185 carries a roller 187, which engages the groove 188 in the drum cam 189, which is secured to the shaft 40. As the shaft 40 70 rotates, the roller 187 working in the cam groove 188 moves the lever 185 back and forth. The lever 185 having the stud 184, which carries the needle, swiveled to it, thus causes the needle to be reciprocated.

75 The inner part of the needle has a pin 190, projecting through slots 191 in the outer part. A pair of springs 192 are fastened to the ends of the pin 190 and the other ends of the springs are secured to the outer part of the needle. These springs hold the head 183 tightly against the end of the outer member of the needle, to grip the string firmly.

Pivoted at 193 on a projection of the stud 85 184, is a member 194, one end of which bears against the end of the inner slidable part of the needle. A light spring 195 keeps it in contact. (See Figs. 22 and 23.) The tail piece of this member 194, is 90 brought in the path of an adjustable movable stop 196, passing through a slot 197 in the bed plate (Figs. 1 and 3). The contact between the stop and tail piece is timed to make the gripping end of the needle 95 grasp and let go of the string at the proper time. The needle operating mechanism works in a larged curved slot 198 in the bed plate.

100 The stop 196 is carried on an arm 199 which is pivoted at 200 to a bracket 201, secured to the under side of the bed plate (Figs. 1 and 3). The arm 199 carries at its lower extremity a roller 202, which engages cams 203 mounted on the disc 204, 105 which is secured to the shaft 40. These cams move the stop into engagement with the tail piece of the member 194, and thus open and close the needle, at the proper time. A spring 205, keeps the roller 202 110 in contact with the disc and cams.

Suitable mechanism for guiding the needle is provided and will now be described. On the intermediate part of the needle, somewhat nearer the gripping end, is secured a yoke 206, which has mounted on its lower part a roller 207. This roller is guided in a cam groove that may be formed in the bed plate, or by a cut out plate 208, secured to the bed plate. Different parts 115 of this cam groove or path are designated by the numerals 209, 210 and 211. A switch cam or member 212 is mounted in such a position as to partially close either the passage 209 or 211.

120 It is the object of these cam grooves which control the movement of the needle, to give the gripping end of the needle an orbital movement. This is desirable and important, in order to insure the gathering together of 130

the cloth or wrapper, preparatory to tightening the knot. The string is guided up to the neck of the package by guides 13^a which are adjacent to each holder.

5 As shown in Fig. 1, the path 211 is partially closed and the roller 207 will on its first movement slide in the path 209. This guides the needle to the proper location, where it takes hold of the string. The 10 string is grasped and the needle is then pulled back by the mechanism heretofore described, and is carried back in the groove 210. While in this position, the string is being brought under the looping members, 15 which will be described hereinafter. Prior to the roller leaving the groove 210, the switch cam 212, is oscillated by suitable mechanism and the groove 209, is practically closed, thus forcing the roller 207, to pass 20 into and along the groove 211. The needle is guided in this groove so that it carries the string around the article to be tied, and through the loops which have been formed. Other suitable mechanism tightens the 25 knot.

The switch cam 212 is mounted on the upper end of a stud 213 (Figs. 22 and 23), which has secured to its lower part a short lever 214. This short lever has pivoted 30 to it at the opposite end 215 a push bar 216 (Fig. 3), which has a slotted connection 217, with a member 218, pivoted at 219 on the bracket 201. The lower part of this member 218 is segmental and engages, at 35 certain times, a pin 220, secured to the disc 204. A spring 221 is confined between the upper part of the member 218, and a block secured to the bed plate. The pin 220, bearing against the segmental part of the member 218, causes the bar 216 to move 40 in one direction, and the spring 221 returns it to the original position. Thus as the pin 220 slides off the segmental part 45 of the member 218, or is engaged by it, the lever 214 is operated, which in turn moves the switch cam 212.

Referring again to the slide 160, a pair of hooks or loopers 222 are mounted therein, so that they may be turned but not 50 moved vertically. Attached to the lower end of the loopers, are pinions 223 in mesh with each other. One of the pinions 223 is engaged by a rack 224 (Figs. 3 and 8), which is slidably mounted in guides 226, 55 secured to the plate 170. As the entire slide is moved inward by its operating mechanism, the loopers and rack and pinions are moved inward, and the end of the rack comes against a stop 227. Due to the slide 60 continuing to move and the rack being stopped, the rack rotates the pinions which in turn rotate the loopers. When they have been rotated a suitable amount (about three quarters of a revolution) the stop is withdrawn and the spring 228, one end of which

is secured to a pin on the rack and the other end to one of the guides 226, pulls the rack back to its original position and thus returns the loopers to their original position.

The mechanism for withdrawing at the proper time, the stop 227 consists of a lever 229, which is mounted at 230 to a bracket, secured to the underneath part of the bed plate (Fig. 15). This lever 229 carries a roller 231, which engages at the proper time 75 a cam groove 232 in the disc 233, which is secured to the shaft 40. The outer end of the lever 229 is engaged by a spring pressed plunger 234, to keep the roller 231 in contact with the edge of the disc 233, and to insure the roller being pushed into the groove 232.

The means for reciprocating the slide 160 will now be described. (See Figs. 3 and 7.) Secured to the lower plate 170 is a 85 bracket 235, which has pivoted at 236 an arm 237. This arm bears a slotted member 238 at its opposite end which, is engaged by the shaft 40, and the outer extremity of the member 238 carries a cam roller 239 90 which engages the cam groove 240, of the face cam 241. This cam 241 is secured to the shaft 40 and is so timed as to move the slide 160 back and forth, in its proper relation to the other parts of the machine. 95

Adjacent the loopers 222, is mounted a block 242, which carries three pins 243 and a guide 244, which are used in conjunction with the hooks or loopers 222, to form the necessary loops in the string. This block has a vertical movement only, in relation to the slide 160, and is secured by a set screw 245 to its operating rod 246. The upper end of this rod is guided by a bracket 247, which is mounted on the slide 160. 100 The lower end is provided with a collar 248 and a spring 249, between said collar and the bottom plate 170. This spring 249 normally tends to pull the block down and keep the end of the rod in contact with the outer end of a lever 250, which is pivoted 105 at 251, in the bracket 235. This lever 250 carries a cam roller 252, which is engaged by a cam face 253, formed in a bracket 254, secured to the bed plate. Another vertical rod 255 is provided, to guide the block 242, and prevent it from turning. 110

Thus, as the cam 241 operates the slide, and the loopers through their mechanism are rotated, the cam lever 250 and cam 253, 115 by means of the mechanism just described, are raising and lowering the block 242, which carries the other parts of the looping mechanism.

While this mechanism is being operated, 120 a presser foot 256 is being utilized, to hold the article to be wrapped and tied firmly in position. Of course, the holders 13 prevent any horizontal movement and the presser foot eliminates any tendency of the 125

article to a vertical movement. The presser foot is pivoted in a bracket 257 secured to the bed plate, and has a long tail piece 258, which carries at its outer end a cam roller 259, for engaging the cam 260, secured to the shaft 29.

A spring 261, secured at one end to a pin 262, mounted in the presser foot and at its other end to a pin or stud, mounted in the bracket 257, holds the cam roller 259 against the cam 260, when the roller is on the dwell portion of the cam as shown in Fig. 7. As the roller leaves this position, the presser foot comes in contact with its article and the spring 261 holds it there, preventing any upward movement of the article.

The main function of the presser foot is to act as a centering device around which the wrapper is gathered and the knot formed. As the wrapper is generally made of a thin or flimsy material, a device of this kind is essential. The presser foot is tapered, so as to be easily disengaged, just prior to the 25 tying of the knot.

After the needle has grasped the string, and has been given its orbital movement around the wrapper and the article to be tied, and after the loops and knot have 30 been formed (as shown in Figs. 29 to 38 which will be described more fully hereafter) the knot is tightened by a certain mechanism provided for the purpose. Just prior to the operation of the knot tightening mechanism, the needle carries the string to a clamping mechanism. It will be recalled that the other part of the string, coming from the supply, is held by the gripping device 90, mounted on the slide 87. The free 40 end α^1 , which has been carried by the needle, is guided to and held by another gripping device 263. (Figs. 37-38), after which the needle is released and starts back, preparatory to grasping a new piece of 45 string.

The gripping device 263 is mounted in the bed plate and consists of a hollow standard 264, in which is mounted the plunger 234, which is normally held down against 50 the lever 229 by a spring 265. This mechanism (Fig. 15) has been previously described, in relation to moving the stop 227 out of engagement with the rack 224. As the cam roller 231 enters the groove 232, the spring 265 forces the lever 229 downward, carrying the stop 227 out of engagement with the rack and also forces the head 266 against the top of the standard, binding the string in the curved groove 267.

55 The head 266 and the upper part of the standard 264 are slabbed off as shown, and the needle near the gripping end is provided with a hump, or protuberance, 268. This hump, or protuberance, 268, allows the 60 string to be spaced away from the needle and

the gripping device 263 is, therefore, able to take a more positive and firmer grip on the string. The needle presents the string to the slabbed-off part of the standard and head 266 of the gripping device and due to 70 this slabbed-off part it is enabled to grab more of the string and thus hold it more firmly.

The knot tied by the mechanism is a reef or square knot and has two distinct loops, 75 which are shown particularly in Figs. 45 to 46. The tightening mechanism shown in Fig. 46, runs up and tightens one of these loops and then other parts of the mechanism tighten the other loop. Part of the 80 mechanism for running up and tightening the first loop is carried on the slide 160 and works in conjunction with a stationary cam mechanism 269, pivoted for adjustment on a stud 270, in the bed plate (Figs. 85 1, 20 and 21).

A hooked lever 271 is pivoted at 272 to a yoke secured to the slide 160 (Fig. 7). Pivoted at 273, to the hooked lever 271, is a link 274, which has a pin and slot connection 90 with a bell crank lever 276 (Figs. 1, 7 and 10). This bell crank lever is pivoted at 277 on a post 278, which is secured to an extension of the slide 160, or to a plate fastened thereto. The part of the post 278 95 above the bell crank lever has a spring 279 coiled around it, which will keep the leg of the bell crank lever, adjacent the horizontal cam edge 280, against said cam 280, as the slide 160 is moved inwards. As the 100 slide 160 is moved inward from the position shown in Fig. 1, the leg of the bell crank lever 276 is urged toward the cam surface 280, and as it continues to move it is engaged by this sloping cam edge 280 and the 105 link 274, through the medium of the spring 281, is forcing the hooked lever 271 in the right direction to run up and tighten the first loop of the knot. Another hooked lever 282 carried on a slide 283 is at the same 110 time forcing the string of the first loop in another direction. The operation of the lever 282 will be described hereinafter.

As the arm of the bell crank lever 276 is guided along the cam edge 280, a pin 284 115 mounted in a counterbored post 285 (see Figs. 4, 10 and 19) secured to the arm of the bell crank lever 276 is riding on the sloped surface 286 of the cam 269 (Fig. 20). When the pin 284 reaches the edge 287 it 120 drops off and, as the slide 160 is then moving back to its original position, the pin rides along the edge 287. As we come to the sudden rise 288 on the cam edge, the hooked lever 271 gives the first loop of the 125 knot a sharp final tightening pull. At the same time, the other hooked lever, is given by suitable mechanism, a sudden movement for the same purpose. The spring 279 returns the bell crank lever and its parts back 130

to normal position, a stop pin 289 (see Figs. 1, 10, 19) limiting the movement of said bell crank lever.

The stationary cam 269 is provided with two adjustments (Figs. 1, 20 and 21). It may be swung on its pivot 270, and held in place by bolts in the arcuate slots 290. The object of this adjustment is to move the position of the part 288 of the cam, and thus give more force to the final pull on the first loop of the knot. The other adjustment is taken care of by rotating the knurled handle of a threaded stud 291, which is swiveled in the slide 292 carrying the cams, and threaded in a flange 293, on the fixed part. A lock nut 294 holds it in position, when located. The object of this adjustment is properly to time the action of the parts operated by the cam and to compensate for wear of parts.

The operation of the hooked lever 282 and slide 283, previously mentioned, will now be described (Figs. 10, 18 and 19). The slide 283 is the upper one of a pair of slides that are mounted in the bracket 295 (Figs. 9, 10, 11, 18 and 19). Said slide 283 is reciprocated by an arm 296, which forms the third arm of the member 117, through the medium of the link 297, pivoted at 298, to an extension of the slide 283. This member 117, as previously described, is operated by suitable mechanism from the cam 167 secured to the shaft 40.

The hooked lever 282 is pivoted at 299, in a bracket 300, which is riveted or otherwise secured to the slide 283. A set screw 301, mounted in a shoulder of the bracket 300, limits the movement of the lever 282 in one direction. The tail, or the end opposite the hook, has secured to it a spring 302, the other end of which is fastened to a stud 303, which is riveted to the upper slide. This stud is slabbed off as shown in Fig. 10 and fits in a slot 304 of the member 305, the slabbed off part of the stud 303 preventing any turning of the member 305. The member 305 has secured to it a spring 306, the opposite end of which is secured to an adjustable connection on the post 307, which is fastened to the lower slide 308.

As the slides are moved in the direction of the arrow 309, Fig. 10, both slides will move, but the lower slide, which has a downward extension 310, will butt against a stop 311, carried on the slide 160, while the upper slide will continue to move in the direction of the arrow 309. The spring 306 will thus be tensioned.

Pivoted at 312, on the hooked lever 282, is a link 313, which is pivoted at its opposite to a pawl 314, pivotally mounted at 315 on the slide 283. As the slide 283 is moved in the direction of the arrow 309, the hooked lever 282 picks up the string and begins to

run up or tighten the first loop, working in conjunction with the hooked lever 271.

Mounted in an extension of the bracket 295, is a short adjustable slide 316, on which is pivoted at 317, a stop 318, having a tail piece 319. A spring 320, one end of which is screwed to the tail piece and the other end to a pin on the slide, holds the movable stop 318 against a fixed stop 321. This movable stop 318 has the same function as the rise 288, on the cam edge 287, that is to give to the first loop of the knot a final tightening pull. Both work simultaneously.

The tensioning of the string after it has been picked up by the lever 282, through the medium of the link 313, makes the pawl 314 assume a position practically at right angles to the slide 283. As the pawl 314 comes in contact with the stop 318, it gives the hooked lever 282 a sharp quick movement in the proper direction, to give the final tightening pull on the string for the first loop, and the pawl 314 then moves past the stop 318. In moving back to its starting position, the pawl 314 forces the stop 318 out of the way and the spring 320 brings it back to its operating position.

The slide 316 has a lug 322, extending down through the extension of the bracket 295. A threaded stud 323 is held against longitudinal movement in this lug by a pair of collars, and said stud 323 is threaded in an extension 324 of the slide 316. A knurled head is provided on the stud 323 for turning it, and a lock nut 325 holds it in position. This provides the adjustment means for the stop 318, so as to time it properly with the rise 288, on the cam edge 287, and with other movements on the machine.

After the first loop has been tightened, the downward extension 310, on the lower slide 308, tightens the second loop. This is accomplished by virtue of the stop 311, on the slide 160, being moved out of the way as the slide 160 is reciprocated. This stop 311 holds the lower slide, until the upper slide has made its maximum movement and stretched the spring 306. The stop 311 then being moved out of engagement with the extension 310, the spring 306 forces said extension against the second loop and runs it up and tightens it. This is shown particularly in Fig. 38.

When the second loop is being tightened, both hooked levers 271 and 282 are moved out of engagement with the first loop. The string is being held by the gripping devices 90, and 263, and the tensioning device carried by the curved arm 114 is helping to tighten both loops of the knot.

After both loops have been tightened and the knot formed, the cutting mechanism des-

gnated generally as 142 is operated to cut the string. This cutting mechanism after cutting the string holds the loose end of the string between it and the tension device 5 140, so as to provide the part a^1 of the string that is to be grasped by the needle for the next operation, as previously described.

The operation of this cutting and holding 10 mechanism will now be described. The mechanism is carried on the slide 87, which carries the tensioning devices. A bar 326, with a cut out part 415, fits on the slide 87, and is held thereto by a screw 327. Screws 328 15 hold a plate 329 on the bar 326, said screws 328 being arranged so as to allow a slight vertical movement of the plate 329. This plate has, at one end, a narrowed down and bent up portion 330. A fixed blade 331 fits 20 in and is held in the cut out part 415 of the bar 326. Adjacent to this fixed blade is a movable blade 332, which has a slot 333, with studs 334 passing through said slot. A retaining plate 335 fits against the movable blade 332. The studs 334, one of 25 which has a spring 336 between its head and the retaining plate, hold the parts in contact and allow the movable blade to be easily reciprocated.

30 The movable blade is reciprocated by means of a bell crank lever 337, pivoted at 338 to an arm 416, either secured to or integral with the slide 87. One arm of the bell crank lever works in a notch 339, in the 35 movable blade 332. The other arm of the bell crank lever is pivoted to a rod 340, which is mounted in an extension 341 of the bracket 295. This rod has a head at its outer end, and between said head and the 40 extension 341 is a spring 342, which normally tends to keep the cutting mechanism in the position shown in Figs. 10 and 12.

When the slide 87 is moved outward, the rod 340 causes the bell crank lever 337 to 45 operate the cutting mechanism, to cut and hold the string, and the parts assume the position shown in Figs. 11 and 13.

The movable blade is provided with a cam edge 343, which cooperates, when the 50 mechanism is functioning, with a cam edge 344 on a plate 345. This plate 345 is yieldingly held to the plate 329, by screws and springs 346. The opposite end of the movable blade has a rounded nose 347, adjacent 55 to the cutting edge 348, and a light spring 349 is located alongside of the cut out part 350.

When the mechanism is being operated, the string rides under the part 330 of the 60 plate 329. When the movable blade is brought to the position shown in Fig. 13, the string rides up on the nose 347 and into the cut out part 350, against the cutting edge 348. The spring 349 prevents the

string from getting out of the pocket 350. 65 As the movable blade is then moved to the position shown in Fig. 12, the cutting edges of both blades have passed and the string has been cut. The end of the string attached to the wrapped package is free, but it is necessary to hold the end coming from the source of supply, to provide the part a^1 of the string previously mentioned.

70 Due to the amount of play between the plate 329 and the bar 326, the string readily slides between these two members and, after the string has been cut and is between these two members, the cooperating cam edges 343 on the movable blade, and 344 on the plate 345, force the plate 329, tightly against the bar 326 and the string is held there, until pulled away by the needle.

75 After the article has been wrapped and tied, suitable mechanism is provided to eject it from the holder on the carrier. This 80 mechanism consists of a U shaped bar 351 (Fig. 7). The shorter leg of said bar ejects the article and for this purpose, as previously mentioned, a segment of the supporting ring 9 has been cut away. The longer leg of the bar bears against the cam 260, which also controls the presser foot. The 85 ejector is guided in a bracket 352, which is secured to the bed plate, and a keyway 353 is formed on the longer leg of the ejector. A pin 354 acts as key, to work in the keyway 90 95 353 and prevent the ejector from turning. A spring 355, one end of which is attached to a lug in the extension 352 and the other end to a pin on the bar, keeps the ejector in contact with the cam. When the longer leg of the ejector is on the low part of the cam, the shorter leg is forcing the article from the holder. A chute 356 is secured to the bed 100 plate, on which the articles drop and are 105 guided to a suitable container.

110 As previously explained, the shaft 40 is revolved by suitable sprocket and sprocket wheels from the shaft 29. This shaft in turn is rotated by a set of gearing 357, from the sleeve 358, mounted on the fixed stud 359 (Fig. 3).

115 This fixed stud 359, is secured in the leg 2, and the sleeve 358 has pinned to its outer end a hand wheel 360, for manipulating the machine by hand when it is necessary to make any adjustments, or for any other reason. A loose pulley 361 is mounted next on the sleeve, and adjacent to the loose pulley

120 is a tight pulley 362, which is the main driving pulley and is secured to the sleeve. The pinion 363 is secured to the sleeve, between the fixed pulley and the shoulder on the stud 359. A collar 364, pinned to the stud, keeps in position the sleeve and the parts 125 mounted thereon.

125 The set of gearing 357 has distinct novel features. The pinion 363, which is secured

to the sleeve 358, has on its front part a set of teeth 365 (Fig. 26), and a blank space 366. On its rear part, there is a set of teeth 367 and a blank space 368. Certain teeth 369 are common to both front and rear parts of the pinion.

The gear has on its front half a cut out part 370, in which the segment 371 can work back and forth, the segment being loosely 10 mounted on the shaft 29. The remaining part of this half is provided with teeth 372. The front half is bolted or otherwise held to the rear half at 373. The rear half of the gear is provided with teeth 374, and a blank 15 space 375.

As shown in Figs. 24 and 25, the machine is ready to start a cycle. The teeth 365 engage the teeth 372 and are rotated in the direction of the arrows, and the blank space 20 368 is passing by the teeth 374. The common teeth 369 engage the teeth on the gears and the teeth 367 engage the teeth 374. It is thus seen that the shaft 29 is rotated until the edge 376 of the segment comes up 25 to the pinion. At this time the beginning of the blank part 375 on the gear 359 is approaching the pinion. Therefore, it will be seen that the teeth 365 on the pinion will engage the teeth 377 on the segment and the 30 segment will ride in the cut out part 370 but will impart no movement to the machine until the edge 376 comes in contact with the edge 378 of the cut out part. By that time the end of the blank space 375 has been 35 reached and the teeth on the pinion will be engaged by the teeth 374, on the gear.

The isolated tooth 379 on the segment maintains the relation between the gear and pinion, in case the machine should be turned 40 backwards at any time.

This momentary stopping of the mechanism comes just after the first loop of the knot has been drawn tight. This is when the knot would be in the position shown in 45 Fig. 42. The rise 288 on the cam surfaces 287 causes the hooked lever 271 to give a sharp tightening pull on the first loop of the knot, simultaneously with the pawl 314 coming in contact with the stop 318, giving the 50 hooked lever 282 a similar sharp tightening pull. This runs the first loop up and tightens it.

However, it has been found, particularly 55 in dealing with a wrapper that is stiff, that before the second loop could be run up and the knot finally tightened, the stiff wrapper naturally tending to open would loosen the first loop so that although the knot were perfectly tied it could very readily be slipped off the package. In dealing with muslin or a wrapper of a very soft nature this gearing could very well be eliminated and a continuous drive used.

The mechanism only stops a fraction of a 60 second and the parts are so timed, as previ-

ously explained, that this final tug on the first loop holds the string tight around the gathered neck of the package until the second loop is tightened and the knot completed.

Means are provided for preventing any back lash, or backward movement, of the machine during the interim of rest. A disc 380 is fixed to the end of the shaft 40, and a pawl 381 is mounted on the leg 2. This pawl 70 75 engages a notch 382 in the disc, at the time when the machine is stopped, and thus prevents any backward movement (see Figs. 1, 3 and 20).

As previously explained, a mechanism is 80 provided for stopping the machine, in case the string breaks or becomes tangled prior to entering the machine. It has been shown how if the string should break the slide 134 would come in contact with the vertical slide 135, and force said vertical slide 135 downward thus operating the stop mechanism. The stop mechanism would also be operated, if a knot or tangled part of the string came 85 up to the eye 84 in the member 85, as shown 90 in Fig. 6. This mechanism will now be described.

Mounted in a bracket 383, secured to the bed plate, is a pin 384, having a spring 385 encircling it. One end of the spring is secured to the pin and the other end to the bracket, and the spring is wound, to force the handle 386, which is secured to the pin, upwards. A hub 387, provided with a flange, is secured to the opposite end of the pin 384, and the flange has a notch 388 cut on its periphery.

The member 85 is pivoted at 389, in a yoke 390 secured to the bracket 383, and is provided at its inner end with a tooth 391, 105 adapted to engage the notch 388, and a toe or projection 392, upon which the vertical slide 135 rests when the machine is in operation. The vertical slide 135 works in a groove cut in the bracket 383, and is held in place by a plate 393, screwed to the bracket 383. A screw 394, mounted in the bracket 383, acts as a stop, to prevent the handle 386 from being raised too high when the tooth 391 is released from its notch 388.

Pivoted on the handle 386, at 395, is a link 396, which has, near its lower end a slot 397, in which is located the headed screw 398, which is threaded into the lever 399. The lever 399 is pivoted at 400, to an extension 401 from the slide 402, which is mounted by pin and slot connections 403, to the legs 2 and 3. The opposite end of the lever 399 is pivoted at 404 to a short lever 405, which is in turn pivoted at 406, to an extension 407, secured to the leg 2 of the machine. The levers 399 and 405 form a toggle joint and, in order to prevent it going past dead centre on its downward movement, a stop pin 408 is provided.

A spring 409, one end of which is attached to the lower end of the link 396, and the other end of which is attached to a pin on the lever 399, is used to keep the levers 399 and 405 in position, and prevent them from rising or breaking the toggle joint, when the machine is in the operating position as shown in Fig. 45.

The slide 402 has a bifurcated end 410, which moves the belt shifting lever from the working position of Fig. 45, to the loose pulley, or to a position shown in Fig. 7. The belt shifting lever is pivoted at 411 to a bracket 412, secured to the leg 2 of the machine. The large spring 413, one end of which is attached to the leg 2 and the other end to the slide 402, moves the slide over positively, when the toggle joint formed by the levers 399 and 405 has been broken.

The slot 397 in the link 396 allows the belt to be shifted from the tight to the loose pulley or vice versa without interfering with the mechanism mounted on the bracket 383.

From the foregoing, it will be clear that when the tooth 391 is disengaged from the notch 388, either by the member 85 being pulled upward, because of a knot in the string, or by the projection 392 being forced downward, by a break in the string, the machine will be immediately stopped by the action of the spring 385 forcing upwards the handle which in turn pulls the link up and, through the mechanism just described operates the belt shifting lever.

A brief description of the operation of the machine will follow, as it is thought the operation has been made fairly clear from the foregoing.

Prior to starting the machine, the string *a*, is threaded through the hole 84 in the member 85, and thence through the tensioning devices on the slide 87, up to the cutting and holding mechanism 142. The string is cut off by the fixed blade and is held in the mechanism 142, thus providing the part *a'* of the string that the needle grips.

Considering the machine as in operation, with all the holders containing a piece of blue *b*, and a cloth covering *c* while the machine is in the position shown in Fig. 1, the operator would be laying a piece of cloth in the pan 15 and forcing a piece of blue with the covering into the holder 13, under the pan. At the same time the needle, looping, tensioning and tightening mechanism would be operating to tie up the piece of blue adjacent to these mechanisms and the ejecting device would be forcing a piece of blue properly wrapped and tied from the holder at the next station, thus leaving an empty holder to come to the filling station on the next cycle of the operation.

The clutch 48 being disengaged from the shaft 40 which carries all the cams to operate the needle, the looping, tensioning, and

tightening mechanism, this mechanism will not operate while the carrier wheel is being turned. As the pin 73 engages one of the notches in the carrier the clutch 48 engages the shaft 40 and this mechanism commences to function.

Figs. 29 to 38 show particularly the operation of the looping and knot tightening mechanism. Starting at Fig. 29, the cloth *c*, and the blue *b*, is shown in position as it arrives at the station where it is tied. The needle has just been brought over by its operating mechanism and is about to grip the part of the string designated *a'*. None of the other parts have as yet been moved.

Passing to Fig. 30, it will be noted that the needle has grasped the thread and drawn it under the projection on the string depressing lever 176, and over the guide 244 and the pins 243. The slide 160 then commences to move inward, and the string depressing lever 176 forces the string down, so as to insure it going under the hooks of the loopers 222.

Fig. 31 shows the slide moved inward a little more, with the string under the hooks of the loopers 222 and over the pin 243 and the guide 244. In this view, the needle has moved over more and is starting to bring the string against a guide 13^a, which runs from the bottom of the holder 13 to the top, where it is curved to guide the string to the proper starting place, to gather in the cloth. As the slide 160, starts to move inward, the block 242, carrying the pins 243 and the guide 244, starts to move upwards under the control of its actuating mechanism previously described.

Fig. 32 shows the slide 160 moved further inward, with the string being lifted upward by the pins 243, and guide 244, against the guide 13^a, but still held under the hooks of the loopers 222. The string has left the depressing lever 176 and is now being brought under the raised end 330 of the plate 329, on the cutting and holding mechanism 142.

Fig. 33 shows the slide 160, moved still further. The string has been slid over the curved top of the guide 13^a and is starting to gather in the cloth *c*, preparatory to getting it in a position to be tied. The block 242, carrying the pins and guides, has been raised higher and the loopers 222 have started to revolve. The string is now approaching the hooked lever 271 mounted on the slide 160. The presser foot 256 has been brought down on the blue by its actuating mechanism, and prevents any tendency of the blue to be raised while being tied. The presser foot acts as a centering device, around which the cloth is gathered and the loops for the knot are formed, and is not removed until the first loop of the knot is tightened.

Fig. 34 shows a further movement of the

parts. The loopers have turned, so as to start forming the loops, a^2 and the wrapper has been gathered in a little more. The block 242, carrying the pins 243 and the 5 guide 244, has been raised to its limit and the presser foot is still in contact with the blue.

In Fig. 35, the parts have been still further advanced. The loopers 222 have been 10 turned as far as they can go, which is about three quarters of a revolution, and the loops a^2 are formed on said loopers, while the hooked tightening levers 271 and 282 are almost in a position to take hold of the 15 string. In this view, the needle is shown in a broken line position, which it assumes preparatory to the position shown in Fig. 36. The position as shown by the broken lines in Fig. 36, corresponds to the view of 20 Fig. 39. In Fig. 39 the position is somewhat distorted, for clearness of illustration.

In Fig. 36, the needle is shown after it has carried the string through the two loops a^2 and to the gripping device 263, which has 25 grasped the string. The cloth has been entirely gathered up and the hooked levers 271 and 282 are approaching the position they take, when they tighten the first loop. In 30 this figure the loopers are just ready to return to their normal position and disengage themselves from the loops a^2 which have been formed.

Fig. 37, shows the position after the needle has released the string and been 35 drawn back through the loops a^2 . At this time, the slide 87, carrying the tensioning mechanism, is starting to move out and the gripping device 90, on the end of the slide 87, has grasped the string. The curved 40 lever 114, carrying the two studs 104 and 107, is starting to move away from the slide and the hooked lever 282 is working past the 45 guide 244 as the slide 283, carrying the said hooked lever, starts to move inward and the slide 160, carrying the guide 244, starts to move outward. The position of the string in Fig. 37 corresponds approximately to the 50 position shown in Fig. 40, that is the two loops have been formed and the end of the string is passed through them.

The hooked lever lifts that part of the string designated a^3 which is between the two loops and shifts it, approximately from the position shown in Fig. 40 to that shown 55 in Fig. 41, or 38, thus placing it in position so that the first loop or knot may be run up and tightened and then the second may be formed.

Fig. 38, shows the two hooked levers as 60 they start to run up and tighten the first loop of the knot. From this view, it will be plainly seen that, after the first loop has been tightened, the downward extension 310 on the lower slide is moved inward, running up and tightening the second loop and com-

pleting the knot. The movement of the curved lever away from the slide 87 also puts a very strong tension on the string and performs the larger part of the work of actually tightening the knot. 70

The position of the string, as shown in Fig. 38, would correspond to that shown in Fig. 41. While the first loop is being tightened, the presser foot leaves the blue and the cloth is drawn tightly together, as 75 shown in Fig. 42. The hooked levers 271 and 282 then pass out of engagement with the string and the downward extension 310, as the slide 308 runs up, tightens the second loop, the arm 114 tensioning the string 80 causes the knot to be drawn absolutely tight, giving the finished knot as shown in Fig. 43.

Fig. 44 shows the completely wrapped and tied package.

After the knot has been tied the gripping 85 devices 90 and 263 are released, and the parts are restored to their original position for the next cycle.

The operation of the ejecting mechanism 90 and the mechanism for stopping the machine, in case there is no blue in the holder or the string breaks, has been described.

From the foregoing description, it is evident that numerous changes may be made in the machine, without departing from the 95 scope of the claims.

What I claim and desire to secure by Letters Patent is the following:

1. In a package tying device, the combination of a carrier for carrying partially wrapped packages to a tying station, means for tying a string about the open end of the wrapper on the package, a presser foot for keeping the article in position and to act as a centering device for the wrapper while being gathered, and means for operating the presser foot. 100

2. In a package tying device, the combination of means for forming two loops in the string, means for passing the free end of the string through the loops and means for tightening the loops. 110

3. In a package tying device, the combination of means for tying a string about one end of a partially wrapped package, 115 and means for cutting the string and holding the end of the string coming from the supply, said means comprising a fixed blade, a movable blade, and means to reciprocate the movable blade. 120

4. In a package tying device, the combination of means for tying a string about one end of a partially wrapped package, and means for cutting the string and holding the end of the string coming from the supply, said means comprising, a movable slide to carry the mechanism, a block secured to said slide, a fixed blade secured to the block, a movable blade adjacent the fixed blade, means to reciprocate the movable blade, said 125 130

means consisting of a bell crank lever pivoted on the slide, one arm of the bell crank lever engaging the movable blade and the other arm engaging a yielding member 5 mounted in a fixed bracket.

5. In a package tying device, the combination of means for tying a string about one end of a partially wrapped package, and means for cutting the string and holding the end of the string coming from the supply, said means comprising, a movable slide to carry the mechanism, a block secured to said slide, a fixed blade secured to the block, a movable blade adjacent the fixed 15 blade, said movable blade having a rounded nose at one end to guide the string and a notch to confine the string while the cutting edges of the blades pass each other to cut the string and means to reciprocate the movable blade.

6. In a package tying device, the combination of means for tying a string about one end of a partially wrapped package, and means for cutting the string and holding the end of the string coming from the supply, said means comprising a movable slide to carry the mechanism, a block secured to the slide, a fixed blade secured to the block, a movable blade adjacent the fixed 25 blade, means to reciprocate the movable blade, a plate mounted on the block, said plate provided with a raised part at one end to guide the string between the plate and the block, and means to force the plate and the block to bind or hold the string between said plate and block.

7. In a package tying device, the combination of means for tying a string about one end of a partially wrapped package, and means for cutting the string and holding the end of the string coming from the supply, said means comprising, a movable slide to carry the mechanism, a block secured to the slide, a fixed blade secured to the block, a movable blade adjacent the fixed blade, means to reciprocate the movable blade, a plate mounted on the block, said plate provided with a raised part at one end to guide the string between the plate 40 and the block, and means to force the plate to bind or hold the string between the plate and the block, said means comprising another plate yieldingly mounted on the first mentioned plate, said plate being provided 45 with a cam edge to cooperate with a cam edge on the movable blade.

8. In a package tying device, the combination of means for tying a string about the open end of a partially wrapped package, means for cutting and holding the end of the string coming from the supply and means for tautening that part of the string.

9. In a package tying device, the combination of means for tying a string about one end of a partially wrapped package,

means for cutting and holding the end of the string coming from the supply, and means for tautening that part of the string, said means comprising a holding mechanism mounted on a slide, a bifurcated member 70 pivotally mounted on the slide and a pair of jaws to impinge on the string, the jaws being mounted on the slide between the arms of the bifurcated member.

10. In a package tying device, the combination of means for tying a string about the open end of a partially wrapped package, means for cutting and holding the end of the string coming from the supply, and means for tautening that part of the string, 75 said means comprising a holding mechanism mounted on a slide, a bifurcated member pivotally mounted on the slide, means to force the bifurcated member upward to tauten the string, said means operated by a slide carrying the looping mechanism, a pair of spring pressed jaws mounted between the arms of the bifurcated member, and a fixed eye mounted on the slide for the 80 passage of the string.

11. In a package tying device, the combination of means for guiding the string to the neck of the package, means for forming two loops in the string, means for passing the free end of the string through the loops, 85 means for shifting the portion of the string between the loops, means for grasping and holding the free end of the string, means for holding the end of the string near the supply, means for running up the first loop or 90 knot to the neck of the package, means for giving a final tightening pull to the first loop, means for running up the second loop or knot, means for tensioning the string 95 while the loops are being tightened and 100 means for cutting the string.

12. In a package tying device, the combination of a needle provided with a gripping jaw for the free end of the string, means for giving said jaw an orbital movement 110 about the end of a partially wrapped package, and means for tying the string about the open end of the partially wrapped package.

13. In a package tying device, the combination of a needle provided with a sliding gripping jaw, to grasp the free end of a string, means for operating the gripping jaw means for giving the gripping jaw an orbital movement about the open end of a 115 partially enveloped package, and means for tying a string about the open end of the partially enveloped package.

14. In a package tying device, the combination of a needle provided with a movable 125 gripping jaw to grasp the free end of a string, a lever for actuating the gripping jaw, means for actuating the lever, means for giving the gripping jaw an orbital movement about the open end of a partially 130

enveloped package and means for tying a string about the open end of the partially enveloped package.

15. In a package tying device, the combination of means for carrying a partially wrapped package to a tying station, means for tying a string around the open end of the partially wrapped package, a presser foot, a cam to move and hold the presser foot out of engagement with the partially wrapped package, a spring for holding the presser foot in engagement with the partially wrapped package and an ejecting mechanism operated by the cam.

16. In a package tying device, the combination of means for tying a string about the open end of a partially wrapped package, said means comprising means for forming two loops in the string, means for passing the free end of the string through the loops, means for shifting the portion of the string between the loops, means for running up the first loop or knot to the neck of the package, and means for tightening the second loop.

17. In a package tying device, the combination of a needle having a gripping jaw at its end, a slide carrying looping members, means for moving the needle and operating the gripping jaw to grasp a string and bring it in contact with the looping members, means for reciprocating the slide and rotating the looping members to form the loops, means for moving the needle through the loops and depositing the free end of the string in a gripping device and means for tightening the loops to form a reef knot.

18. In a package tying device, the combination of means for tying a string about the open end of a partially wrapped package, said means comprising, means for guiding the string to the neck of the partially wrapped package, means for forming two loops in the string, means for passing the free end of the string through the loops, means for shifting the portion of the string between the loops, means for grasping and holding the free end of the string, means for holding the end of the string near the supply, means for running up the first loop or knot to the neck of the package, means for giving a final tightening pull to the first loop, means for running up the second loop or knot, means for tensioning the string while the loops are being tightened, means for cutting the string and holding the end coming from the supply and means for tightening that part of the string.

19. In a package tying device, means for tying a string about one end of a partially enveloped package, said means comprising a guide with a curved upper portion to guide the string to the neck of the partially enveloped package, means for forming two loops in the string, means for passing the

free end of the string through the loops and means for tightening the loops.

20. In a package tying device, means for tying a string about the open end of a partially enveloped package, said means comprising means for guiding the string to the neck of the partially enveloped package, means for forming two loops in the string, said means comprising a lever to depress the string, a pair of loopers or hoops, means to rotate the loopers, a slide on which the loopers are mounted, means to reciprocate the slide, a block carrying a guide and a plurality of pins to engage the string in conjunction with the loopers, said block being carried by the slide, means for moving the block up and down, means for passing the free end of the string through the loops, and means for tightening the loops.

21. In a package tying device, the combination of means for tying a string about the open end of a partially wrapped package, said means comprising means for guiding the string to the neck of the package, means for forming two loops in the string, means for passing the free end of the string through the loops, said means comprising a needle with a jaw for gripping the free end of the string, the needle having a guide roller working in a groove, a cam to move the end of the needle carrying the free end of the string through the loops, and a lever and a movable stop to open the jaw of the needle and release the string, means for tightening the loops or knots, and means for holding and tensioning the string while being tightened.

22. In a package tying device, means for tying a string about one end of a partially wrapped package, said means comprising means for forming two loops in the string, means for passing the free end of the string through the loops, means for shifting the portion of the string between the loops, said means comprising a guide mounted on a block, means to move the block up and down, a slide, means to reciprocate the slide, a hooked lever pivoted on another slide at right angles to the aforesaid mentioned slide, means to reciprocate the second slide, and means to tighten the loops.

23. In a package tying device, means for wrapping a string about one end of a partially wrapped package, comprising means for forming two loops in the string, means for passing the free end of the string through the loops, means for grasping and holding the free end of the string, said means comprising a hollow standard, a headed member mounted in the standard, a spring to depress the headed member and confine the string between the head and top of the standard, and a cam to allow the spring to operate at the proper time, means

- for holding the string near the supply and means for tightening the loops.
24. In a package tying device, means for tying a string about the open end of a partially wrapped package, having in combination, means for forming two loops in the string, means for passing the free end of the string through the loops, means for holding the string, means for running up the first 10 loop or knot, said means comprising two hooked levers mounted on slides at right angles to each other, means for running up and tightening the second loop or knot, and means for tensioning the string while the 15 loops are being tightened.
25. In a package tying device, means for tying a string about the open end of a partially wrapped package, having in combination, means for forming two loops in the 20 string, means for passing the free end of the string through the loops, means for holding the string, means for running up and tightening the loops or knots, means for tensioning the string while the loops are being 25 tightened, said means comprising a curved arm carrying studs to engage the string and means for moving the curved arm away from the slide carrying the string.
26. In a package tying device, means for 30 tying a string about the open end of a partially wrapped package, having in combination, means for forming two loops in the string, means for passing the free end of the string through the loops, means for holding
- the string, means for running up and tightening the loops or knots, means for tensioning the string while the loops are being tightened and means for cutting the string and holding the end coming from the supply.
27. In a package tying device, the combination of means for tying a string about the open end of a partially wrapped package and means for stopping the tying mechanism if the string breaks in said mechanism or becomes tangled prior to entering the mechanism.
28. In a package tying device, the combination of means for tying a string about the open end of a partially wrapped package, 50 and means for stopping the tying mechanism if the string breaks in said mechanism or becomes tangled prior to entering the mechanism, said means comprising a belt shifting member, a slide to operate the belt 55 shifting members and means to operate said slide.
29. In a package tying device, the combination of means for tying a string about one end of a partially wrapped package and 60 driving means so arranged as to cause a momentary stopping of the machine during the tying of the knot.

This specification signed this 25 day of October, 1923.

WILLIAM RYDER.
EDWARD RYDER.
